CAMILLO OLIVETTI, OF IVREA, ITALY.

TYPEWRITING MACHINE.

Application filed June 30, 1925, Serial No. 40,568, and in Italy November 26, 1924.

The present invention relates to typewriting machines, and more particularly to the type bar actions with which such machines are equipped; its object being the provision 5 of an improved type bar action which insures the transmission of the forces set up by the depression of a key lever to the associated type bar to operate the latter without producing any strains or stresses which 10 would tend to act injuriously upon the moving parts.

According to the invention, each key lever is linked to a bell-crank lever which, in turn, operates a rod that is connected 15 through the intermediary of a sub-lever to the associated type bar; the arrangement of parts being such that the key lever, link and bell-crank move in a common vertical plane, and the sub-lever and type bar in a radial 20 plane, while the rod is situated at the intersection of these two planes and, hence, in a sense lies in both of them, whereby any twisting or torsional strains are avoided, due to the pivotal connections between the 25 several parts.

The invention also resides in rigidly connecting together the upper and lower notched segments wherein the type bars and sub-levers are mounted and guided for 30 movement vertically as a unit, such movement being utilized to effect the shift from upper to lower case and vice versa without entailing any movement of the platen, which latter remains stationary. Other and 35 further objects and improvements are involved in the invention and will be explained in the course of the following detailed description.

In the accompanying drawings:

40 Figure 1 is a side view of the complete lever system comprised in the invention and applied by way of example, to one of the central type bars; the notched guide plates and other supporting parts are shown in section, but all devices not definitely related to the actual invention are omitted.

45 Fig. 2 is a front view, showing the connected upper and lower notched segments and, also, one of the side type bars and its associated sub-lever.

50 Fig. 3 is a detail view of the pivot carrier of one of the bell-cranks.

55 Fig. 4 is a plan view of a slightly modified form of key lever.

Figs. 5 and 6 are fragmental views in side 55 elevation and plan, respectively, of one of the keys.

Figs. 7 and 8 are side views of further modified forms of key levers.

Referring more particularly to the drawings, the key lever 2 which, for general purposes, may be regarded as typical of all the levers of that class, terminates at its front end, as usual, in a key 1 and is pivoted at its rear end to a horizontal rod or wire 3 60 that extends the entire width of the key board. This wire 3 is supported in a groove formed in a notched guide plate 4, the ends of which are fastened to the opposite side members of the machine frame; the notches 65 in the plate being equidistantly spaced and receiving therein the rear ends of the key levers, which latter are thereby caused to move in parallel vertical planes.

The key lever 2 has pivotally connected 70 to its central portion at 5, the lower end of a vertical link 6, the upper end of which is pivotally connected at 7 to the upper arm of a bell-crank 8. The latter is mounted at 75 its apex on a pivot pin 9 carried by a forked or slotted stud 10 (Fig. 3) which is provided for a purpose subsequently explained, said stud being mounted in the front plate 11 and held in place by a nut 28. The lower 80 arm of the bell-crank is connected by a pivot 27 to the front end of a rod 12 that carries on its threaded rear end a head 15, so that by rotating said head in the proper direction the length of the rod may be adjusted as desired; and said head, in turn, 85 carries a pivot 16 which passes through the central portion of a sub-lever 13.

The sub-lever 13 is pivoted at its lower 90 end on an arcuate wire 14 mounted in a slot formed in a segmental plate 19 which likewise 95 extends the entire width of the key board and is provided with spaced guide notches to receive the aforesaid ends of the sub-levers; this plate forming the lower member of a bodily-movable unit, of which 100 the upper member is constituted by the type bar segment 23, as hereinafter more fully described. The upper end of the sub-lever carries a pin or stud 17 having a head 18 (Fig. 2), and this stud works in a slot 20 105 formed in the heel of the type bar 21; the latter being pivotally mounted on an arcuate wire 22 which is disposed in a slot formed

in the previously-mentioned plate or segment 23. The last-named element is provided with guide slots for the type bars, as usual, and is disposed directly above the segment 19; the two segments being rigidly connected together at their ends, as represented in Fig. 2, to enable them to move bodily up or down as a unit, for which purpose they are pivotally connected at their backs with the rear wall or member of the machine frame by pairs of links 30 and 32 that jointly form a parallel-motion device. The upper links 30 are attached at opposite ends to pivots 31 and 34 carried by suitable lugs or projections on the plate 23 and rear frame wall, respectively, and the ends of the lower links 32 are similarly connected to the segment 19 and the aforesaid frame wall at 33 and 34; but this particular link mounting, while preferred, can be replaced by any other mounting which will permit the desired vertical movement of the unit, the latter having also connected to it the cushion 24 whereon the type bars rest in normal or lowered position. The vertical movement in question serves, as will be understood, to raise or lower the type basket so as to bring the types on the type bars into upper or lower case printing position with relation to the printing line on the roller platen 26, which latter remains stationary during the case-shift operation which may be effected in the usual way by means of the shift keys.

The letter-feeding and ribbon-vibrating operations may likewise be effected in the ordinary manner by the action of the key levers and type bars, respectively; but since the intermediate devices which directly produce these operations form in themselves no part of the actual invention, they have not been illustrated. For all present purposes, it is believed sufficient to state that the various key levers are provided with depending projections 35 which, when a key is depressed, are caused to bear down upon the transversely-arranged universal bar 36 which is connected in some suitable way with the carriage escapement. The type bars, on the other hand, are shaped adjacent the points where they engage the suspension wire or pivot 22 in such a manner as to bear upwardly against an arcuate bar 37 which is connected with the escapement vibrator and also with the segment 23 so that it not only actuates the vibrator but overlies the wire 22 and thus prevents accidental disconnection of the type bars therefrom.

As will be apparent from the foregoing, the wires 14 and 22 form concentric arcs, the center of which is the printing point O on the platen 26. The sub-levers 13 which are pivoted on wire 14 and the type bars 21 which are pivoted on wire 22 move vertically in radial planes, each lever and its corresponding type bar in the same plane so that

the notches therefor in the segments 19 and 23 are in radial alinement, as indicated in Fig. 2; but each key lever 2 and the associated link 6 and bell-crank 8, however, move in the same vertical plane. The location of the pivots 16 which connect the sub-levers to the heads on the rods 12 is determined by the intersection of the planes of the key levers 2 and bell-cranks 8 with the radial planes of the type bars and the sub-levers. The vertical arms of all the bell-cranks have the same length, but the horizontal (or substantially horizontal) arms thereof are of different lengths according to the type bars with which they are associated. Because of this arrangement, the supporting plate 11 which carries the studs 10 is made of arcuate shape, and the studs themselves can be turned or adjusted in the openings in said plate so that the pins 9 may be brought into horizontal position.

In consequence of the above arrangement, it will be seen that each rod 12 lies in the line of intersection between the radial plane defined by the associated sub-lever and type bar and the vertical plane defined by the corresponding key lever, connecting link and bell-crank. The said rod may thus be regarded as situated in both planes specified so that it can transmit the forces from key lever to type bar under identical conditions throughout the key board and without setting up any injurious resultant strains or stresses regardless of the inclination of the type bars; and all key actions, both those at the center of the key board and type basket and those at the sides or ends thereof, will operate with the same rapidity and lightness of touch. As all the key levers 2 must be spaced at practically the same distance apart, the angles between the type bars necessarily vary because they are determined by the intersection of the several parallel vertical planes wherein the parts 2, 6 and 8 lie with the arc formed by the row of pivots 16 (i. e., the junction points of the rods 12 with the sub-levers 13). This variation also satisfies the practically necessary condition that the type carried by the type bars be spaced a sufficient distance apart in their horizontal position of rest, and the fact that the space occupied by the types in such position increases with the increasing of the angular bend of the type bar at A-A (Fig. 1). The key levers may, however, be offset centrally, as represented in Fig. 4, to compensate in certain circumstances for slight inaccuracies or irregularities in positioning the notches in the plates 4, 19 or 23.

As further regards the key levers, these parts may have return springs 25 attached to them so as to effect the desired quick return movement of the associated type bars; the tension of the springs being regulated by means of screws 29 are mounted in a pro-

jecting portion of plate 4 and with which the springs are engaged at one end, the other end of the springs being engaged with the key levers. The keys proper 1 with which said levers are provided may be formed from the metal of the levers themselves, as shown in Figs. 5 and 6, by striking out and then bending into horizontal position a small circular disk to which the key 10 cap is directly secured.

Increased resilience and lighter touch may also be obtained by forming the rear portion of the key lever as illustrated in Figs. 7 and 8. In both cases, it will be observed that the strip of metal from which the lever is constructed is about half as long again as the lever shown in Fig. 1, and that this excess length, so to speak, occurs at the rear end of the lever and is bent backward upon 20 the body of the lever, thus forming a fork. The free end of the said bent portion is connected to the lower end of the link 6, so that the length of the lever arms remains the same as before, in spite of the actual increase 25 in the length of the lever blank. In the form represented in Fig. 7, the bent part overlies the rear portion of the lever, whereas in Fig. 8 it underlies such portion, and the said rear portion of the lever is offset 30 downwardly from the front portion in Fig. 7 and upwardly therefrom in Fig. 8. In the latter case, the free end 38 of the bent part to which the end of link 6 is pivoted is turned upward, as shown; this construction 35 having the advantage that a very light touch is sufficient to effectively operate the type bar, and that a very quick stroke of the bar itself is obtained, due to the fact that the upper arm of the lever first comes to bear 40 upon the end 38 of the lower arm and then transmits its motion to link 6, and after having overcome the inertia of the system returns to its normal position.

I claim as my invention:—

1. A type bar action for typewriters, comprising a key lever; a bell-crank fulcrumed at its apex above the key lever; a depending link pivoted at its upper end to the upper arm of the bell-crank and at its lower end to the key lever; a pivotally-mounted type bar having a slotted heel; a vertical sub-lever pivotally supported at its lower end and provided at its upper end with a stud which is slidably engaged in the slot in said heel; and a rod pivotally connected at oppo-

site ends to the lower arm of the bell-crank and the sub-lever.

2. A type bar action for typewriters, comprising a key lever; a bell-crank fulcrumed at its apex above the key lever; a depending link pivoted at its upper end to the upper arm of the bell-crank and at its lower end to the key lever; a pivotally-mounted type bar having a slotted heel; a vertical sub-lever pivotally supported at its lower end 65 and provided at its upper end with a stud which is slidably engaged in the slot in said heel; and a rod pivotally connected at its front end to the lower arm of the bell-crank and provided at its rear end with a longitudinally-adjustable head which is pivoted to the sub-lever. 70

3. A type bar action, according to claim 1, in which the key lever, the link and the bell-crank are disposed in a common vertical plane, while the type bar and sub-lever are disposed in a common radial plane which intersects said vertical plane along a substantially-horizontal line; and in which the rod normally coincides with said line of intersection so as to lie in both planes. 75

4. In a typewriter, the combination of a vertically-movable unit embodying spaced upper and lower notched segments rigidly connected together at their adjacent ends; a parallel-motion device for guiding said unit in its movements embodying upper and lower pairs of links pivotally connected at opposite ends to the corresponding segments and the rear member of the typewriter 80 frame; a set of type bars pivotally supported and guided by the upper segment; a set of sub-levers operatively connected with the type bars and pivotally supported and guided by the lower segment, said sets of type bars and sub-levers being movable vertically bodily with the respective segments; a set of key levers; a set of bell-cranks, one individual to each key lever and sub-lever; pivoted at their apices above the key levers; a depending link pivoted at its upper end to the upper arm of each bell-crank and at its lower end to the corresponding key lever; and a rod pivotally connected at its front 85 end to the lower arm of each bell-crank and at its rear end to the corresponding sub-lever. 90

In testimony whereof I affix my signature.

INC. CAMILLO OLIVETTI.
